UNITED STATES PATENT OFFICE.

SILL HAMILTON, OF CARROLLTON, ALABAMA.

HAMMER.

1,303,792.

Specification of Letters Patent. Patented May 13, 1919.

Application filed June 14, 1918. Serial No. 240,090.

To all whom it may concern:

Be it known that I, SILL HAMILTON, a citizen of the United States, residing at Carrollton, in the county of Pickens and State 5 of Alabama, have invented new and useful Improvements in Hammers, of which the following is a specification.

This invention relates to new and useful improvements in means for operating a hammer and the principal object of the invention 10 is to provide means for operating a blacksmith's hammer by a foot pedal.

Another object of the invention is to provide a device of this character which is simple and durable in construction, reliable and 15 efficient in operation and one which can be manufactured and placed upon the market at a minimum cost.

The invention also consists in certain other 20 features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is an elevation of the invention. Fig. 2 is a like view from the opposite side and showing the hammer in raised position.

In these views 1 indicates the anvil supported by the usual block 2. 3 indicates an upright located a suitable distance from the anvil. To the upper end of this upright is pivoted the handle 4 of the hammer 5. The end of the handle is slightly curved as at 6. A lever 7 is pivoted intermediate its ends to an upright 8 and the front end of this lever 40 extends to a point adjacent the block 2 and the end thereof is provided with a foot pedal 9. The other end of the lever is connected by a link 10 with the handle 4 and a coil spring 11 has one end connected with the link 10 and its other end connected with the lever 7 beyond the upright 8.

It will thus be seen that a smith standing

in front of the anvil can place his foot on the pedal 9 so as to lower the lever 7. This, 50 through the link 10, will raise the hammer and as soon as the pressure of his foot is removed from the pedal the spring 11 will cause the hammer to strike the anvil with a heavy blow. In this way both hands of the 55 smith are free to manipulate the article being operated upon and the only effort required on the part of the smith is the pressure upon the foot pedal.

A flat recoil spring 12 is secured to the 60 upright 3 and has its upper end provided with a U-bolt for engaging the handle of the hammer and holding it in raised position.

It is thought from the foregoing description that the advantages and novel features 65 of my invention will be readily apparent.

I desire it to be understood that I may make changes in the construction and in the combination and arrangement of the several parts, provided that such changes fall within 70 the scope of the appended claims.

What I claim is:—

1. A device of the class described comprising a support, a hammer having its handle pivoted to said support, a lever, means for 75 pivotally supporting the same intermediate its ends, a link connecting one end of said lever with said handle, and extending substantially at right angles to said lever, a foot pedal at the other end of said lever and a 80 coil spring connecting said link with the lever.

2. A device of the class described comprising an anvil, a hammer coöperating therewith, a support to which the end of the 85 hammer handle is pivotally connected, means for oscillating the handle including a foot operated lever and a link connecting the lever to the handle, a flat recoil spring carried by the support and a U-shaped member carried by said spring for engaging the handle to hold the hammer in raised position. 90

In testimony whereof I affix my signature.

SILL HAMILTON.
